UNITED STATES PATENT OFFICE.

EDWIN FRED BUERGERMEISTER, OF CHICAGO, ILLINOIS.

COMBINATION KITCHEN CABINET AND REFRIGERATOR.

Application filed August 29, 1927. Serial No. 216,069.

My invention relates to a novel combination kitchen cabinet and refrigerator, and has for its primary object the provision of a device that will combine in a single unit 5 all the facilities and advantages hitherto only to be obtained by the use of a refrigerator and a kitchen cabinet in separate form.

Another object of my invention is to provide a device of the kind described, having 10 additional concealed means adapting it, when desired, to cook food.

A further object of my invention is to provide means in a device of the kind described having novel means adapting it to 15 be extended.

Further objects and advantages of the construction and method herein employed will appear more fully in the hereinafter specification when taken in connection with the 20 accompanying drawings, in which

Figure 1 is a front elevation of my device.

Figure 2 is an end view from the left.

Figure 3 is an end view from the right.

Figure 4 is a longitudinal sectional view 25 on line 4—4 of Figure 2.

Figure 5 is a longitudinal view, showing the cabinet in extending position.

Figure 6 is a plan view of Figure 5, with parts broken away.

Figure 7 is a section taken on line 7—7 of Figure 6.

Figure 8 is a view of one of the ends of one of the extensible sections.

Figure 9 is a plan sectional view on line 30 9—9 of Figure 4.

Figure 10 is a plan view of the bottom of the cabinet.

Figure 11 is a perspective view of the refrigerating container.

In the drawing, the numeral 15 designates 40 the supporting legs of the cabinet having the bottom 16, secured by screws 17 to the end rails 18, having the slots 19 adapted to receive the upper part of the rails 21 and 21' the lower part of which rides in the slots 19, the rails 21 and 21' having depending shoes 22 and 22', which engage with the slot 20.

As best shown in the extended position 45 of the cabinet in Figure 6, the ends of the cabinet comprise the lefthand extension member 23 and the righthand extension member 24, the lefthand end 23 including the bottom fastening member 25, the compartment 26, the compartments 28 having shelves 28', it being evident that the left-

hand member may be drawn from the closed position shown in Figure 1 to the position illustrated in Figures 5 and 6, by means of the aforesaid rails 21 and 22 and slots 19 60 and 20.

The extending mechanism of the right-hand end of the cabinet is symmetrical with that of the lefthand end 23 and comprises the rail 21' and shoe 22' adapted to ride in slots 19 and 20. The righthand end 24 further comprises the compartment 27, compartment 29, both left and righthand members 23 and 24 being also provided with swinging doors 30 and 31. 32 and 33 are 70 the front panels of the left and righthand ends 23 and 24; and 34 and 35 the back panels. 36 and 37 are compartments in the left and right hand ends of the extension members 23 and 24 as illustrated in Figures 75 6, 7 and 8. The compartments 36 and 37 are provided with drawers 38 and 38'.

40 is a compartment in the lefthand end adapted to receive a receptacle 41 having a plurality of slats 42 adapted to support ice. 80 43 is a compartment therein adapted to contain the water from the melting ice, to be drained therefrom by the pipe 44. 45 is a work board situated in the middle part of the cabinet, and beneath the work board are 85 pockets 46, 47 and 48, for the purpose of holding food articles of various description.

At the rearward part of the work board 45, are compartments 52 suitably mounted on the stationary part of the cabinet. The 90 compartments 52 have a plurality of drawers 53 for the purpose of containing various articles of food, spices, etc. Beneath the compartments 52 and the drawers 53 are bin pockets 54, which may accommodate 95 other articles.

The mode of operation of my device and its uses will now be readily apparent from an inspection of the drawings, and may be briefly described as follows:

In normal position the cabinet will be as 100 shown in Figure 1. When it is desired to extend the cabinet, the ends of the two sections 23 and 24 are drawn apart, thereby disclosing the central bin and receptacle containing central compartment, the lugs 21' 105 22' and the slots 19 and 20 providing the usual guide grooves. It will be noted that while I have provided my device with an ice containing receptacle, it will be readily understood that my device is adapted to 110 accommodate the modern electrical refrig-

eration units, it then being necessary merely to make the usual switch connections for that purpose. In the righthand end of my cabinet the electrical stove 51 provides a 5 convenient method of preparing food, and by means of the usual insulation, the heat generated, even while the stove is in actual operation, will not interfere with the refrigeration of the lefthand end compartment. This is particularly true of the electrical mode of cooking food, since when the current is turned off, the stove will quickly return to the mean temperature of the cabinet.

15 By the method and construction herein illustrated and described, I have been enabled to greatly economize space, and at the same time to save labor on the part of those who having occasion to use the cabinet may 20 take advantage of its practical features by not being obliged to go from the refrigerator to the stove and to the kitchen cabinet, this being essential when these devices are in separate units, and differently placed.

25 While I have herein described and in the accompanying drawing illustrated a preferred form of my invention, I do not thereby desire or intend to limit myself specifically thereto. It will be understood that 30 minor changes of construction and arrangement may be made, if desired, without departing from the spirit and scope of the invention as defined in the appended claims.

What I claim as new and desire to secure 35 by Letters Patent is:—

1. A device of the kind described comprising a cabinet having a plurality of drawers centrally positioned beneath a stationary work board forming a part of said 40 cabinet, and a pair of extension end members slidably connected to said cabinet, and normally overlying said work board but uncovering the said work board when in extended position.

45 2. In combination, a kitchen cabinet and refrigerator comprising a main receptacle containing portion, a plurality of ends extendibly connected to said portion, one of said ends including means for receiving a 50 refrigerating instrumentality, the other of said ends including means for receiving a cooking instrumentality, and additional means whereby the main receptacle containing portion is concealed when said ends are 55 in normal unextended position.

3. A combination kitchen cabinet and refrigerator having extension ends longitudinally movable relatively to a central portion having a plurality of pockets containing drawers, one of said ends having means to receive a source of refrigeration therein, the other of said ends having means to receive a source of heat therein, a work board

secured over said pockets, said work board being uncovered in operative position when 65 said ends are extended.

4. A kitchen cabinet having a central section containing a plurality of bins located at the top, bottom and side of said central section, a pair of compartment containing 70 end members connected and longitudinally movable relatively to said central section in a manner to cover and uncover a work board fastened to the central section and also to cover and uncover bins at the top of the 75 central section, said extension end members being supported on rails sliding in grooves provided in the bottom of said central section.

5. A kitchen cabinet having a central section containing a plurality of compartments, a pair of extension end members longitudinally movable relatively to said central section, thereby covering and uncovering said plurality of compartments and also covering and uncovering at the same time a work board fastened over said plurality of compartments, rails connected to said end members, said rails having shoes slideable in slots provided in members attached to said 90 central section.

6. A kitchen cabinet having a central stationary section mounted on supporting legs, said stationary section containing compartments, a pair of extension end members slidably connected with said central section, said extension end members having rails slideable in slots provided in rails attached to the bottom of said central section, a work board secured to said central stationary section and means whereby said end members when drawn into extended position are adapted to uncover the compartments in the central section and the work board, and to cover said compartments and said work board when in unextended position.

7. A device of the kind described, comprising in combination, a cabinet having a central stationary section mounted on supporting legs, a pair of extension end members slidably connected with said central section, a work board secured to said central stationary section, said work board being operatively uncovered when said end sections are placed in extended position, one of said extension end members having a receptacle for ice therein, the other of said extension end members having means for receiving a source of heat, said extension end members, when drawn to extended position, being also adapted to uncover bins provided in a rearwardly extending part of said central section.

In testimony whereof I have signed my name to this specification.

EDWIN FRED BUERGERMEISTER.
